OR D 14,076

DESIGN FOR A FIRE-PLACE FRONT.

Design No. 14,076, dated July 10, 1883.

UNITED STATES PATENT OFFICE.

JOSEPH A. READ, OF PHILADELPHIA, PA., ASSIGNOR TO GILBERT COMBS,
JOHN BAWDEN, AND JOHN H. BAWDEN, ALL OF FREEHOLD, N. J.

DESIGN FOR A FIRE-PLACE FRONT.

SPECIFICATION forming part of Design No. 14,076, dated July 10, 1883.

Application filed May 5, 1883. Term of patent 14 years.

To all whom it may concern:

Be it known that I, JOSEPH A. READ, a citizen of the United States, and a resident of Philadelphia, Pennsylvania, have invented or 5 produced a new and original Design for a Fire-Place Front, of which the following is a specification.

My design is fully shown in the accompanying photographs.

10 The main or central panel has ornaments mostly of a floral character, and also a representation of a pair of birds and of a nest with eggs. Surrounding the central panel is a frame, the ornamentation of which is a central stem 15 with branching leaves and blossoms. At the top of the structure is a grated opening, around which the frame is carried, the ornamentation of this part of the frame, however, being slightly different from that of the other portions. 20 Outside of the frame, and extending completely around the structure, is a beaded border.

The top may be either rounded, as shown in Fig. 1, or flat with rounded corners, as shown 25 in Fig. 2, this change not altering the character of the design.

I claim—

1. The design for a fire-place front, said design comprising a panel with ornamentation of a floral character, and with a representation 30 of a bird's nest and birds, as shown and described.

2. The design for a fire-place front, said design comprising the central panel and surrounding frame, with ornamentation, as shown 35 and described.

3. The design for a fire-place front, said design comprising the central panel, the grated opening at the top of the same, and the frame surrounding the panel and opening, as shown 40 and described.

4. The design for a fire-place front, said design comprising the central panel, the surrounding frame, and the beaded border, all ornamented as shown and described. 45

In testimony whereof I have signed my name to this specification in the presence of two subscribing witnesses.

JOSEPH A. READ.
